UNITED STATES PATENT OFFICE

163,400

PAINT DRYING AND BAKING OVEN

John V. Marr, Fayetteville, N. C.

Application May 1, 1950, Serial No. 9,622

Term of patent 14 years

(Cl. D14—3)

To all whom it may concern:

Be it known that I, John V. Marr, a citizen of the United States, residing at Fayetteville, in the county of Cumberland and State of North Carolina, have invented a new, original, and ornamental Design for a Paint Drying and Baking Oven, of which the following is a specification, reference being had to the accompanying drawing, forming part thereof.

The single figure of the drawing is a perspective view of an end and side of a paint drying and baking oven, showing my new design, the other end and side being similar in appearance, and the top of the apparatus continuing in the same pattern as on the sides of the apparatus.

The characteristic features of my new design for a paint drying and baking oven reside in the

portions shown in full lines in the drawing, and in the inverted generally U-shaped bows in uniformly spaced relation within the outer covering, substantially as shown.

I claim:

The ornamental design for a paint drying and baking oven, substantially as shown and described.

JOHN V. MARR.
